[57] CLAIM

The ornamental design for a shoe upper, as described.

DESCRIPTION

FIG. 1 is a left side elevational view of a shoe upper showing our new design;
FIG. 2 is a right side elevational view thereof;
FIG. 3 is a top plan view thereof;
FIG. 4 is a front elevational view thereof; and,
FIG. 5 is a rear elevational view thereof.

FIG. 1

FIG. 2

FIG. 3

FIG. 4

FIG. 5

UNITED STATES PATENT AND TRADEMARK OFFICE
CERTIFICATE OF CORRECTION

PATENT NO. : Des. 362,110
DATED : September 12, 1995
INVENTOR(S) : David Presser

It is certified that error appears in the above-identified patent and that said Letters Patent is hereby corrected as shown below:

Column 2, under "DESCRIPTION", after the Figure descriptions add the following statement:

-The broken line showing of a shoe sole in the figures is environmental only and forms no part of the claimed design.--

Signed and Sealed this
Twelfth Day of March, 1996

Attest:

BRUCE LEHMAN
